BLOUSE CONSTRUCTION FOR DRESSES

Armigene Roderick Johnson, New York, N. Y.

Application November 27, 1951, Serial No. 258,356

4 Claims. (Cl. 2-74)

1

The present invention relates to women's garments and embodies, more specifically, an improved garment of unitary construction particularly useful in garments, such as uniforms and the like, wherein freedom of movement and stylish appearance are combined with features that enable the garment to be quickly put on and taken off.

In nursing service a nurse's activities are such as to require considerable freedom of movement within a garment that is being worn and, to provide such freedom of movement, existing garments have been made in such form that they are not stylish in appearance. It is an object of the present invention, accordingly, to provide a garment such as, for example, a nurse's uniform, having attractive and stylish appearance, but at the same time providing sufficient freedom of movement to enable the wearer to discharge all of the duties required during service.

A further object of the present invention is to provide a garment of the above character which is readily put on or taken off.

The attainment of the foregoing objects is accomplished by the provision of a unitary construction having top and skirt portions that meet at a waist portion to which there is secured a slip pants and top, the top portion of the garment, in the region of the armholes, being formed of such structure as to allow complete freedom of movement of the arms of the wearer.

Further objects of the present invention will become apparent as it is described in connection with the accompanying drawings, wherein

Figure 1 is a view in front elevation showing a garment constructed in accordance with the present invention;

Figure 2 is a partial view similar to Figure 1 showing the top of the garment opened;

Figure 3 is an exploded view showing the slip pants and slip top in details;

Figure 4 is a detail view showing the waist portion only of the garment of Figure 1;

Figure 5 is a view showing the elements of Figure 4 that comprise the front of the waist portion;

Figure 6 is a plan view of the back portion of the waist of Figure 4;

Figure 7 is a view similar to Figure 4 showing a modified form of the invention;

Figure 8 is a plan view showing the back portion of the waist of Figure 7; and

Figure 9 is a plan view showing the front portions of the waist of Figure 7.

Referring to the above drawings, and particularly to Figures 1 to 6, inclusive, a garment is

2

shown at 10 as being formed of a skirt portion 11 and top portion 12, these portions meeting at the waist portion 13. Within the skirt portion 11 there is provided a slip pants 14 that is secured 5 to the garment 10 in the region of the waist 13. A slip top 15 is provided within the waist portion 12, the straps 16 of which may be tacked or otherwise secured to the shoulder portions of the garment. It will be observed that the front edge 17 of the slip top 15 is secured to the inner face of the right-hand front panel 18 of the top portion 12, while the front edge 19 of the slip top 15 is secured to the inner face of the left-hand front panel 20 of the top portion 12.

As will be seen from Figure 2, the top edge 21 of the right leg of the slip pants 14 is sewed to the inner top of the skirt portion 11 of the garment at the waist thereof, the top 22 of the left leg of the slip pants being similarly secured in 10 the left interior side of the waist portion of the garment, the forward portion 23 thereof thus opening with the left front panel of the top portion of the garment. As used herein, the terms "right" and "left" refer to the positions as seen 20 in the drawings, rather than as the garment is worn. As will be seen in Figure 3, the adjacent edges of the tops of the slip pants overlap at the front and rear portions thereof, and the adjacent edges in the crotch are formed with relatively 25 wide hems 24 and 24A which overlap in their normal positions.

The skirt portion of the garment is formed with a front panel 25, the right edge 26 of which extends upwardly and, in the region of the waist 13, meets the edge 27 of the front panel 20 in overlapping relationship to the rear panel 18. As illustrated in Figure 2 the edge 26 of the front panel 25 is removably secured to the underlying skirt portion in the upper region of the skirt and adjacent the waist portion of the garment. In this fashion the front of the garment, including the top and the upper portion of the skirt thereof, may be opened to facilitate putting the garment on and taking the garment off. Suitable buttons 28 and button holes 29, or other securing means, may be provided in the top and skirt portion of the garment in order to maintain it in the normal position illustrated in Figure 1.

With reference to the top portion of the garment, Figures 4, 5, and 6 illustrate the manner in which it is made. The front panels 18 and 20 are formed with sleeve pieces 30 and 31, respectively, slits 32 and 33 being formed in the region thereof. These slits form reentrant portions which are adapted to receive, respectively, gussets

34 and 35 that are formed on the back portion 36 of the garment. In order to illustrate, more effectively, the manner in which these elements are assembled, the legends A to K have been applied to the drawings. Legends A and B indicate the points at the back of the neck where the front and back portions are secured together, seams between these portions being indicated from A to C and B to D on the left and right front panels and on the left and right sides of the back portions, respectively. The sleeve piece 30 is formed into the sleeve of the garment by joining the spaced edges DH by a suitable seam, while the left sleeve is formed by joining the spaced edges CG in like fashion. The right-hand gusset shown in Figure 4 is formed by sewing together the edges DE on the right front panel and the back panel, respectively, while the left-hand gusset is formed by sewing together the edges CF on the left-hand front panel and the back panel. The edges EK and FJ are then sewed together to complete the top portion of the garment. By providing the gusset formation in the region of the armholes great freedom of movement is afforded the wearer and yet a stylish appearance is preserved in the garment.

In the form of the invention illustrated in Figures 7, 8, and 9 the sleeve pieces are formed on the back panel, and the gussets are formed on the respective front panels. In all other respects the garments are alike. In this fashion the garment of Figures 7, 8, and 9 is formed of right and left front panels 37 and 38, the right panel being formed with a gusset 39 and the left panel with a gusset 40. The back panel of the garment is shown at 41 and is provided with right and left-hand slits 42 and 43, respectively. The assembly of the portions is along the same lines as illustrated in Figures 4 to 6, points AB and JK being identical in the two modifications. The back panel 41 is formed with sleeve pieces 44 and 45 corresponding, respectively, with the sleeve pieces 30 and 31.

It will be apparent that features of the garment of this invention are suitable for use in men's and children's apparel as well as apparel for women, and while the invention has been described with specific reference to the accompanying drawings, it is not to be limited save as defined in the appended claims.

I claim:

1. A woman's garment of unitary construction, comprising top and skirt portions meeting at a waist portion, the top portion being formed of

three pieces of fabric, one of which is a back portion having at least one gusset in the region of an armhole, and the other two pieces of which are front portions, at least one of which is formed with a reentrant portion adapted to receive the gusset, and seams uniting the three pieces of fabric forming said top portions.

2. A woman's garment of unitary construction, comprising top and skirt portions meeting at a waist portion, the top portion being formed of three pieces of fabric, one of which is a back portion having at least one reentrant portion in the region of an armhole, and the other two pieces of which are front portions at least one of which is formed with a gusset in the region of an armhole to be received in the reentrant portion, and seams uniting the three pieces of fabric forming said top portion.

3. A woman's garment of unitary construction, comprising top and skirt portions meeting at a waist portion, the top portion being formed of three pieces of fabric, one of which is a back portion having at least one gusset in the region of an armhole, and the other two pieces of which are front portions, each having a sleeve piece and at least one of which is formed with a reentrant portion adapted to receive the gusset, and seams uniting the three pieces of fabric forming said top portion.

4. A woman's garment of unitary construction, comprising top and skirt portions meeting at a waist portion, the top portion being formed of three pieces of fabric, one of which is a back portion having sleeve pieces and at least one reentrant portion in the region of the armhole, and the other two pieces of which are front portions at least one of which is formed with a gusset adapted to be received in the reentrant portion, and seams uniting the three pieces of fabric forming said top portion.

ARMIGENE RODERICK JOHNSON.
